Primary Examiner — Susan Moon Lee(74) *Attorney, Agent, or Firm* — Michael B. Fein; Eckert Seamans Cherin & Mellott, LLC(57) **CLAIM**

I claim the ornamental design for a pet grooming comb, as shown and described.

DESCRIPTION

FIG. 1 is a bottom perspective view of a pet grooming comb showing my new design;

FIG. 2 is a bottom view of the pet grooming comb;

FIG. 3 is a top plan view thereof;

FIG. 4 is an end elevation view thereof;

FIG. 5 is an opposite end elevation view thereof;

FIG. 6 is a side perspective view thereof; and,

FIG. 7 is an opposite side perspective view thereof.
